UNITED STATES PATENT OFFICE.

THOMAS O'TOOLE, OF WINNIPEG, MANITOBA, CANADA.

SPRING-BED.

1,165,280.

Specification of Letters Patent. Patented Dec. 21, 1915.

Application filed February 9, 1915. Serial No. 7,056.

To all whom it may concern:

Be it known that I, THOMAS O'TOOLE, a citizen of Canada, residing at Winnipeg, in the Province of Manitoba and Dominion of Canada, have invented new and useful Improvements in Spring-Beds, of which the following is a specification.

This invention relates to improvements in spring beds of that class in which the wire mattress fabric is supported on the upper ends of vertically arranged coiled springs which are mounted on a frame, the object of the invention being to provide an improved bed spring of this class which obviates the swaying motion that has heretofore been an objectionable feature in such spring beds; which provides means to keep the mattress fabric level when the bed is not in use; which keeps the edge wire of the mattress fabric stiff and under tension at all times; which stiffens the edges of the mattress fabric when the bed is in use and so that a person can lie on the same without danger of rolling off; which enables the tension on the edge wire to be varied as may be desired; and which consists of parts that are adapted to be readily assembled and disassembled so as to greatly facilitate packing, storing and shipping the said spring beds.

The invention consists in the construction, combination and arrangement of devices hereinafter described and claimed.

In the accompanying drawings: Figure 1 is a longitudinal sectional view of a spring bed constructed in accordance with my invention. Fig. 2 is a vertical transverse sectional view of the same. Fig. 3 is a detail perspective view of one corner of the same. Fig. 4 is a detail horizontal sectional view of the same on the plane indicated by the line *a—a* of Fig. 3. Fig. 5 is a detail vertical sectional view of the same on the plane indicated by the line *b—b* of Fig. 3.

The base, supporting frame of my improved spring bed comprises a pair of longitudinally arranged side bars 1 which are made of angle iron and a series of transverse bars 2, which are also preferably made of iron and which have their ends bent at right angles as at 3 and riveted to the inner sides of the vertical webs of the angle iron side bars 1. The coiled springs 4 which bear under the wire mattress fabric 5 have their lower ends secured on the cross bars 2 at suitable points, any suitable number of said coiled springs being employed.

The mattress fabric 5 may be of any suitable construction and is here shown as formed of longitudinal wires 6 and cross wires 7. This mattress fabric is provided with an endless edge wire 8 of suitable gage and which extends around the ends and sides of the mattress fabric.

My invention relates especially to improved means for engaging the edge wire and holding the same under tension, to keep the mattress fabric level when not in use and to prevent the same from sagging at the sides when not in use and to also co-operate with the coiled springs in the support of the mattress fabric and the weight of the person or persons using the bed.

In accordance with my invention I provide a bracket 9 for each corner of the bed. Each bracket is a single casting, comprising a base 10 to bear on one of the bars 1, at one end of the same, and an upstanding outwardly extending curved arm 11. The arm of each bracket is formed at its outer, upper end with a pair of vertical, spaced lugs 12, each of which has an open bearing slot 13. The base 10 of each bracket is provided on its under side, near its inner end, with a downwardly extending stud 14 to enter an opening punched in the bar 1 and said base is provided at its outer end with a downwardly extended and inturned flange 15 to engage the end of said bar as shown. The brackets while thus firmly connected to the ends of the bars 1 by their studs 14 and flanges 15 may be readily detached from said bars, when taking down the bed, no rivets or other fastening devices being employed for this purpose.

The corners of the edge wire 8 are slidably engaged in the rounded grooves 16 in the outer sides and near the upper ends of the lever standards 17. One of these lever standards is provided for each bracket 9 and is arranged in the space between the lugs 12 and provided at a suitable distance from its upper end with trunnions 18 which engage in the slots 13 of said lugs so that the lever standards are detachably pivotally mounted in the brackets and may be readily mounted therein or removed therefrom.

Coiled retractile springs 19 are provided for drawing inwardly on the lower ends of the lever standards and hence causing their upper ends to move outwardly and put and keep the edge wire 8 under tension. These springs 19 are here shown as attached to

the bars as at 20 which are spaced from the ends of the bars 1 and as connected to the lower ends of the lever standards by links 21 and eyes 22, the latter being engaged with notches 23 near the lower ends of the lever standards and said link wires extending through and being freely slideable in openings 24 in the bearings at the ends of the frame. The tensioning spring 19 5 may be of any suitable gage and strength according to the desired tension of the edge wire 8. The lever standards may be readily disconnected from the spring 19 by merely discharging their lower ends from the link 10 eyes, when taking down the bed for purposes of repair, storage, transportation or the like. I also provide braces 26 to coöperate with the lever standards and spring 19 in imparting the requisite tension to the edge wire. 15 These braces are preferably made of iron and each is provided near its upper end with an opening 27 through which that portion of the edge wire which forms one end of the mattress fabric passes. The opposite end 20 of each brace is provided with an open slot 28 and is thereby forked and adapted to bear on a guide wire 29 which connects two of the bars 2. A coiled retractile spring 30 is mounted on each guide wire and bears at 25 one end against one of the bars 2 and at the other end against the forked inner end of the brace and hence the said springs press the braces outwardly and cause the latter to coöperate with the edge wire under stress. 30 When disassembling the spring bed the braces 26 may be readily lifted and disconnected from the guide wires, as will be understood. 35 Having thus described my invention, I 40 claim:—

1. In a spring bed of the class described a frame, brackets at the corners of the frame, lever standards pivotally mounted in the

brackets, tensioning springs connected to the frame and also connected to the lower ends 45 of the lever standards and an edge wire having its corners slidably engaged with the upper ends of the lever standards.

2. In a spring bed of the class described a frame, brackets at the corners of the frame, 50 lever standards pivotally mounted in the brackets, tensioning springs connected to the frame and also connected to the lower ends of the lever standards and an edge wire having its corners slidably engaged with the 55 upper ends of the lever standards, said brackets being each provided with a pair of spaced lugs each of which has an open slot, each of the standard brackets being provided with a pair of trunnions pivotally mounted 60 in said slots.

3. In a spring bed of the class described a frame including side bars and cross bars, 65 guide wires connecting certain of the cross bars, brackets secured on the ends of the side bars, lever standards pivotally mounted in said brackets, tensioning springs connected to certain of the cross bars and also connected to the lower ends of the lever standards, an edge wire having its corners 70 slidably engaged with the upper ends of the lever standards, braces connected to those portions of the edge wire which form the ends of the mattress fabric and having their lower ends slidably mounted on the guide 75 wires, and springs exerting outward thrust on said braces and coacting with the latter and with said lever standards and with said tensioning springs to cause the edge wire to be kept under tension. 80

In testimony whereof I affix my signature in presence of two witnesses.

THOMAS O'TOOLE.
